UNITED STATES PATENT OFFICE.

BUTLER AMES, OF LOWELL, MASSACHUSETTS.

BLADE HOLDER.

Application filed February 5, 1920. Serial No. 356,471.

To all whom it may concern:

Be it known that I, BUTLER AMES, a citizen of the United States, and resident of Lowell, in the county of Middlesex and State 5 of Massachusetts, have invented new and useful Improvements in Blade Holders, of which the following is a specification.

My invention relates to edge protecting holders for blades adapted for use with 10 safety razors and the like. It comprises a holding clip for packing such blades and is adapted to be formed of sheet metal or other suitable material.

It has heretofore been customary to pack 15 razor blades in paper or cardboard packages or cartons, the blades being usually individually wrapped in oiled or waxed paper. The cutting edges of such blades are extremely fine and being formed of thin metal 20 may be comparatively easily injured or destroyed by contact with stiff or rigid material. The paper wrapping or cardboard carton is not of sufficient strength to properly protect the blades, and on contact will dull 25 the edges and rough or careless handling will often ruin the blades before use.

It is an object of my invention to provide 30 a holding clip for razor blades or the like which will protect such elements from injury through careless handling. It is an object to provide a holder which will positively and adequately protect the blade edges. It is also an object to provide a holder which 35 may be mechanically formed at small cost from comparatively inexpensive material. It is an object to provide a holder upon which blades may be readily assembled, and from which one or more may be easily detached, the remaining blades being still 40 protected by the holder. Another object of my invention in its more specific aspect is to provide such a clip or holder so formed that it is only possible to assemble blades thereupon in the proper position. Other and further objects and results of my invention will 45 appear as the description proceeds.

For the accomplishment of these desired objects I have provided a blade holder which 50 comprises a comparatively stiff or substantially rigid guard member having overhanging portions out of contact with the cutting edges of the blades and protecting these edges from contact with objects which may injure the fine cutting edge.

55 An important feature as regards the util-

ity of my device lies in the facility and ease with which blades may be removed therefrom. The overhanging portions of the holder act as finger grips and prevent accidental cutting of the fingers in removing a 60 blade. Also in the particular embodiment which I have shown and described hereafter, the holder is formed shorter than the extreme length of the blade to be held and yet 65 longer than the cutting edge thereof so that the edge is fully protected. While the holder is held by means of the overhanging portions between the thumb and forefinger of one hand, the unsharpened ends of the blades may be similarly grasped by the other hand 70 since the end of the holder will not interfere and the blade may thus be removed without danger of cutting either hand or of injuring the blade edges. The fact that the holder is shorter than the extreme length of 75 the blade, greatly facilitates the removal of the blade in the manner just described.

The specific form of holder shown not only has the advantages in use which have just been described but also permits the use 80 of less material and since the ends of the holder are square there is no material wasted in manufacture.

I have shown a preferred form of my invention in the accompanying drawings, in 85 which,

Figure 1 is a perspective view of my improved holder:

Figure 2 is a plan view showing blades 90 assembled thereon:

Figure 3 is a section taken on line 3—3 of Fig. 2: and

Figure 4 is a section taken on line 4—4 of Fig. 2.

The particular embodiment of the invention chosen for the purpose of illustration consists in a holder comprising a channel-shaped member 5 having lateral flanges 6. Adjacent the ends of the channel tongues 7 are struck up out of the holder blank. As 100 shown in Fig. 2, razor or similar blades 8 are placed in the channel member, the tongues 7 passing through the openings 9 in the blades. These openings 9 are formed in a number of types of blades in general use for the purpose of attachment to the razor in using the blade, and are here utilized for another purpose. The upper ends of the tongues 7 are bent down to retain the blades in place. Obviously the length

of the tongues 7 and the height of the flanges 6 will be proportioned according to the number and the thickness of the blades to be placed in each holder. The length of the clip is slightly less than the extreme length of the blades in order to facilitate the removal of the blades which may be readily taken endwise between thumb and forefinger. After removing a blade the tongues 7 may be again bent down to retain the remaining blades.

The width between the flanges 6 is slightly greater than the width of the blades so that they do not contact with either flange. In the illustration, the blade shown is of a single edged type having the openings 9 closer to the back than to the cutting edge. The tongues 7 are accordingly placed closer to one of the flanges 6 than to the other such flange. This eccentric location of the openings and the tongues renders it impossible to place the blades in the holder than in uniform manner with all cutting edges faced in the same direction. The size of the holder and the location and size of the tongues will be varied to suit the particular type of blades with which it is to be used.

While the holder is preferably formed from sheet metal by a stamping process it may be formed of any other suitable material having sufficient rigidity to retain and protect the blades, such material as celluloid, for example. In this case the tongues 7 would be resiliently flexible and would be formed in the bent down position, being flexed up in putting on or taking off blades and returning automatically to the bent down position when released. If

stamped from spring metal the holder 40 would also function in this manner.

Obviously the blades may be individually wrapped in the usual oiled or waxed paper if desired, the tongues 7 passing through openings similar to 9 in the wrapping. 45

I claim:—

1. A holder for razor blades or the like, comprising a substantially rigid member adapted to extend beyond the blade edge, and means on the holder for attaching blades to said holder, the substantially rigid member being shorter than the extreme length of the blade with which it is adapted for use. 50

2. A holder for razor blades or the like, comprising a substantially rigid member adapted to extend beyond the blade edge, and means on the holder for attaching blades to said holder, the substantially rigid member being shorter than the extreme length of the blade with which it is adapted for use but longer than the cutting edge of said blade. 55

3. A holder for razor blades or the like, comprising a substantially rigid member, one side of which is adapted to extend beyond an edge of a blade supported thereon and has overhanging portions adapted to protect the edge of the blade, the upper side of the blade being uncovered and means for attaching the blade to the holder, the substantially rigid member being shorter than the extreme length of the blade with which it is adapted for use, but longer than the cutting edge of said blade. 65 70 75

Signed by me at Boston, Massachusetts this 2nd day of February, 1920.

BUTLER AMES.
